(57) **CLAIM**

The ornamental design for a teaching machine for small children, as shown and described.

DESCRIPTION

The file of this patent contains at least one drawing executed in color. Copies of this patent with color drawing will be provided by the Office upon request and payment of the necessary fee.

FIG. 1 is a top view of a teaching machine for small children showing our new design;

FIG. 2 is a left view thereof;

FIG. 3 is a front view thereof;

FIG. 4 is a back view thereof;

FIG. 5 is a right view thereof;

FIG. 6 is a bottom view thereof; and,

FIG. 7 is a front view of the teaching machine for small children of FIG. 1 shown in an alternate position with a wing lifted.
